DESIGN FOR A LIGHTER OR THE LIKE

Quinlan Terrence Regan, Chartley, Mass., assignor to Evans Case Company, North Attleboro, Mass., a corporation of Massachusetts

Application April 26, 1940, Serial No. 91,982

Term of patent 14 years

To all whom it may concern:

Be it known that I, Quinlan Terrence Regan, citizen of the United States, residing at Chartley, county of Bristol and State of Massachusetts, have invented a new, original, and ornamental Design for Lighters or the like, of which the following is a specification, reference being had to the accompanying drawing, forming a part thereof.

In the accompanying drawing Figure 1 is a side elevation of a lighter or the like showing my new design; Fig. 2 is an end elevation of the same; Fig. 3 is a top plan view of the same.

The dominant feature of my design resides in the top portion shown in full lines in the drawing.

I claim:

The ornamental design for a lighter or the like, as shown and described.

QUINLAN TERRENCE REGAN.
